CABINET DOOR LATCH

Orvel E. Bacon, 1289 Exeter, El Cajon, Calif.

Filed May 25, 1964, Ser. No. 80,126

Term of patent 7 years

(Cl. D50—5)

FIGURE 1 is a perspective view of a cabinet door latch, showing my new design;

FIGURE 2 is a perspective view thereof with the interfitting elements separated;

FIGURE 3 is a plan view thereof;

FIGURE 4 is a side elevational view thereof;

FIGURE 5 is an end elevational view as taken from the right end of FIGURE 4;

FIGURE 6 is an end elevational view as taken from the left end of FIGURE 4; and

FIGURE 7 is a bottom plan view thereof.

I claim:

The ornamental design for a cabinet door latch, as shown.
